UNITED STATES PATENT OFFICE.

ROBERT M. APPLETON, OF BOSTON, MASSACHUSETTS.

CIRCULAR-KNITTING MACHINE.

SPECIFICATION forming part of Letters Patent No. 391,291, dated October 16, 1888.

Application filed January 26, 1888. Serial No. 261,933. (No model.)

To all whom it may concern:

Be it known that I, ROBERT M. APPLETON, a subject of the Queen of Great Britain and Ireland, and a resident of Boston, Suffolk 5 county, Massachusetts, have invented certain Improvements in Circular-Knitting Machines, of which the following is a specification.

The object of my invention is to provide means for so feeding a continuous re-enforcing 10 thread to the spring-beard needles of an ordinary round-knitting machine that said thread can be knitted into the fabric throughout any predetermined portion or portions of the course around the head and allowed to float through- 15 out the remaining portion or portions, the length of the float being as great as desired; and this object I attain in the manner which I will now proceed to describe.

In the accompanying drawings, Figure 1 is a 20 diagram representing in plan view sufficient of an ordinary spring-beard-needle knitting-machine to illustrate my invention. Fig. 2 is a diagram showing a section of the knitted tube produced. Fig. 3 is a sectional view of the combined stitch and presser wheel forming the 25 subject of my invention, and Figs. 4 and 5 are diagrams illustrating different methods of re-enforcing portions of stockings by the use of said combined stitch and presser wheel. Fig. 30 6 is a diagram showing in a flat plane the character of the taper-ended patch referred to hereinafter.

It has long been a desideratum to re-enforce with an additional thread portions of a tube 35 of knitted fabric produced upon a circular-knitting machine employing spring-beard needles; but owing to the construction of such machines this has heretofore been considered impracticable. Recent attempts in this direction have been based upon the plan of cutting 40 or breaking the re-enforcing thread after it has been fed to a certain number of needles of the head, and completing the rotation without feeding any re-enforcing thread to the remainder of the needles, the feeding being resumed 45 when the proper needles are again brought into position. Irrespective of the uncertainty of this method of feeding, however, the method is impracticable, because of the complicated 50 and unreliable character of the mechanism necessarily employed in carrying it out, and

because it cannot be adopted when the re-enforcing thread is of a color different from that of the main knitting-thread, the re-enforcing patch having broken or irregular edges, owing 55 to the fact that there is no means of insuring the feeding of the re-enforcing thread to a definite number of needles or to a definitely-located set of needles in each course.

In carrying out my invention, therefore, I 60 use a continuous re-enforcing thread, which is applied to and forms stitches on a certain number of needles around the head, but fails to form stitches on the remaining needles, and is directed away from the various burrs which 65 operate in conjunction with the needles in a spring-beard-needle machine, the thread always being applied to the same number of needles in each course, and the set of needles which receives the thread in each course bearing 70 a fixed and definite relation to the like set of needles in an adjoining course, so that a re-enforcing patch having a regular outline must necessarily result.

In the drawings, *xx* represent the needles 75 of the machine, *a* being the looping-wheel; *b*, the presser-wheel; *d*, the landing-wheel; *f*, the knocking-over wheel; *g*, the push-back, and *h* the clearing wheel, all constructed and operating as usual in an ordinary knitting-machine of the class to which my invention relates, *i* being the guide which directs the knitting-thread to the looper-wheel *a*. In advance 80 of the looping-wheel *a*, however, is located what I term a "combined stitch and presser 85 wheel," *m*, which has part way around the same projecting teeth of the same character as those of the looping-wheel, and in the remaining portion teeth differing slightly therefrom in the respect pointed out hereinafter, this wheel 90 being employed in connection with a guide, *n*, which receives the re-enforcing thread and directs it to the wheel.

When it is desired to apply the re-enforcing thread to the same needles in each course 95 of stitches, so as to produce a rectangular re-enforcing patch upon the knitted tube, the wheel *m* must have teeth equal in number to the needles of the head; but only a portion of these teeth act to apply the thread to the needles, the 100 rest of the wheel being blank—that is to say, having the spaces between the teeth filled up—

- so that this portion of the wheel serves to press down or close the beards of the needles, the re-enforcing thread consequently running outside of said beards and failing to form stitches on the needles so pressed. Thus, if the re-enforcing patch is to extend, say, half-way around the knitted tube, one-half of the teeth of the wheel *m* would be operative and the other half of the wheel would be blank.
- 10 As there are the same number of teeth in the wheel as there are needles in the head, it follows that each tooth works in conjunction with the same needle in each course; hence absolute certainty in the application of the
- 15 thread must result. It is necessary, however, that there shall be no undue slack in the floating portion of the thread, and that said thread shall, when the blanked portion of the wheel *m* is pressing upon the needles, be carried up,
- 20 so as to be delivered over the tops of the needles, and thus clear the various burrs of the machine which act subsequently to said wheel *m*; hence I form in the blanked portion of the wheel a deep groove, *s*, instead of the shallow
- 25 groove formed in the teeth of the acting portion of the wheel, as shown in Fig. 3. The thread enters this deep groove, and hence is not confined rigidly between the beards of the needles and the blank face of the wheel acting
- 30 upon the same, but lies loosely in the groove and is drawn forward by the pull of the fabric, so that said floating portion of the thread is caused to lie snugly against or cling to the tube of fabric in the process of knitting, thus
- 35 clearing the various burr-wheels which act upon the stitches on the needles.
- My invention also permits the introduction of the re-enforcing-thread in the form of a patch having tapered ends, instead of a rect-
- 40 angular patch, the wheel *m* in this case having a limited number of teeth, more or less than the needles of the head, so that the position of the re-enforcing thread advances or recedes one or more needles in each successive course,
- 45 the number depending upon the sharpness or bluntness of taper desired. (See Fig. 6.) These taper-ended patches of re-enforcing thread may be applied to an ordinary plain-knitted web, or the extra thread may be used
- 50 for re-enforcing one or more taper-ended elastic gussets formed in the tube, as set forth in my patent, No. 243,425, dated June 28, 1881, the stitch and presser wheel in this case having but one tooth more or less than the needles of the head, and a tucked presser-wheel
- 55 being employed in place of the plain presser-wheel *b*, for the purpose of forming the taper-ended elastic gusset by tucking the stitches formed by the main knitting-thread.
- 60 By "tucked presser-wheel" I mean a wheel notched or recessed throughout a portion of its periphery, as shown by dotted lines in Fig. 1, so that on one rotation of the head alternate needles—say, for instance, the needles 1
- 65 3 5, &c.—around a part of the head will not be pressed, but will retain their stitches, these needles being therefore said to be tucked, while

on the next rotation of the head the needles which were before tucked will be pressed and the intermediate needles, 2 4 6, &c., will be tucked, thus producing what is termed a "one-and-one" tuck.

To produce the tapering or inclined ends on the tucked gusset thus made, the periphery of the presser-wheel is so proportioned in respect to the needles in the head that the tucking will not always be upon the same needles. For instance, if there are, say, three hundred needles in the head, and in the first course the needles from 150 to 300 represent the extent 75 of the tucked portion, on the next course the tucked portion may be represented by the needles from 149 to 299, and on the next course by the needles from 148 to 298, and so on.

I have not shown in the drawings any sinker 85 or dividing-wheel such as is usually employed adjacent to the looper-wheel *a*; but such a dividing-wheel may be used, if desired, and one may also be used adjacent to the wheel *m*, although the looper-wheel *a* in most cases performs acceptably the function of a dividing-wheel for said wheel *m*.

In Fig. 4 I have shown a diagram of a stocking having the toe, sole, heel, calf, and knee provided with rectangular re-enforcing patches 95 in accordance with my invention; and in Fig. 5 I have shown a stocking having the heel, calf, and knee provided with taper-ended reinforce patches, and it will be evident that the re-enforcing patches may be applied to any 100 one or more of these portions, as required.

I am well aware that it is a common practice to block or plug the ordinary looping-wheel of a spring-beard-needle knitting-machine for the purpose of forming fancy stripes 105 or other special designs with the main knitting-thread. A small wheel, however, such as the ordinary looping-wheel, is not available for the purpose of introducing a re-enforcing thread, the floating portion of which may extend more than half-way around the head. A wheel for this purpose must, like my combined 110 stitch and presser wheel, have teeth or projections approximating in number to the number of needles in the head—that is to say, the 115 wheel must have precisely the same number of teeth or projections as there are needles or a limited number, more or less.

When the machine has two or more feeds, I may in some cases substitute my combined 120 stitch and presser wheel for one of the loop-wheels of the machine. In all cases, however, care must be taken that the portions of the re-enforcing thread which do not form stitches are so governed as to draw in or cling closely 125 to the tube of fabric which is being produced, so that there will be no entanglement of the floating portions of the thread with the various burr-wheels which act upon the stitches.

I am aware that it has been proposed to introduce a separate thread in a knitted tube produced upon a spring-beard-needle machine by the use of a separate thread-guide operated upon by a cam, so that it is alternately thrown

into position to feed its thread to the needles and moved away from such position; but this device lacks the simplicity of construction and accuracy of operation which are prominent advantages of the combined stitch and presser wheel forming the subject of my invention.

I therefore claim and desire to secure by Letters Patent—

1. The combination of the needles, burrs, presser and knitting-thread guide of a knitting-machine with a re-enforcing-thread guide, and a combined stitch and presser wheel having teeth approximating in number to the number of needles in the head, but blanked throughout a portion of its circumference, all substantially as specified.

2. The combination of the needles, burrs, presser and knitting-thread guide of a knitting-machine with a re-enforcing-thread guide, and a combined stitch and presser wheel having teeth approximating in number

to the number of needles in the head, but blanked throughout a portion of its circumference, and having in said blanked portion a thread-receiving groove of greater depth than the recesses in the acting teeth of the wheel, all substantially as specified.

3. The combination of the needles, burrs, and knitting-thread guide of a knitting-machine with a re-enforcing-thread guide, a combined stitch and presser wheel having teeth approximating in number to the number of needles in the head, but blanked throughout a portion of its circumference, and a notched or tuck presser wheel for the main knitting-thread, all substantially as specified.

In testimony whereof I have signed my name to this specification in the presence of two subscribing witnesses.

ROBERT M. APPLETON.
